UNITED STATES PATENT OFFICE.

AUGUST C. CHRISTENSEN, OF BROOKLYN, NEW YORK.

PISTON GAS-METER.

SPECIFICATION forming part of Letters Patent No. 373,923, dated November 29, 1887.

Application filed March 11, 1887. Serial No. 230,572. (No model.)

To all whom it may concern:

Be it known that I, AUGUST C. CHRISTENSEN, of Brooklyn, county of Kings, and State of New York, have invented certain new and useful Improvements in Gas-Meters, of which the following is a specification.

This invention relates to certain improvements in the gas and steam piston meter for which Letters Patent were granted to me heretofore, No. 340,763, dated April 27, 1886, the improvement serving to adapt the meter in a more perfect manner for the purpose of measuring gas, and more especially natural gas, as it can be accurately run with a pressure from half an ounce per square inch to a pressure of hundreds of pounds per square inch, as the friction between the stationary and movable parts is entirely removed and the piston balanced in such a manner that it responds reliably to the pressure of the passing gas.

The invention consists of a gas-meter the inclosing-casing of which is made in the shape of two cylinders, reciprocating pistons arranged in said cylinders and formed of end disks, and connecting-stems, said pistons being suspended by center rods from carriages which rest on anti-friction balls and ways in a chest at the upper part of the casing. The slide-valves are located at the bottom of the cylinders intermediately between the end disks of the pistons and guided over the outlet-ports by fixed transverse rods, the friction with the bottom of the cylinders being diminished by intermediate anti-friction rollers located in grooves of the slide-valves.

In the accompanying drawings, Figure 1 represents a vertical longitudinal section of my improved gas-meter, taken on line *xx*, Fig. 2. Fig. 2 is a horizontal section of the same on the line *yy*, Fig. 1, with parts of the piston-stem broken away. Fig. 3 is a vertical transverse section taken on line *zz*, Fig. 1. Fig. 4 is a bottom view of the gas-meter. Fig. 5 is a vertical longitudinal section on line *kk*, Fig. 2; and Fig. 6 is a vertical transverse section on line *ll*, Fig. 5.

Similar letters of reference indicate corresponding parts.

The inclosing casing or body of my improved gas-meter is formed of two parallel

hollow cylinders, *A A'*, of equal size, which are closed by heads *A²*, secured thereto, said cylinders being cast in one piece and provided with a chest, *A³*, at the upper part, that extends transversely across both cylinders, and with a bottom, *A⁴*, having vertical passages for the gas. The chest *A³* serves for receiving the usual counter employed in piston meters of this class and for providing the ways *d*, on which the carriages *C C'* are guided, from which the pistons *B B'* are suspended.

The pistons *B B'* are constructed of hollow sheet-metal heads or disks *b b'*, that are united by central hollow or solid stems, *b' b*. The pistons *B B'* are suspended from the carriages *C C'* by vertical rods *b²*, which pass through longitudinal slots at the upper parts of the cylinders and are attached to the carriages *C C'* and the stems *b' b*. The suspension-rods are located centrally between the end disks, *b b'*, so as to properly balance the pistons.

The carriages *C C'* are provided with longitudinal grooves *d'* at their under side, and rest on anti-friction balls or rollers *d²*, which rollers are guided in the grooves *d'* and horizontal ways *d* at the top part of the cylinders *A A'*, as shown in Figs. 1 and 3. By suspending the pistons *B B'* from the carriages *C C'* the friction of the same with the cylinders is entirely removed, while by the balancing of the pistons on the carriages and the lightness of the pistons themselves the uniform and reliable movement that responds even to very low gas-pressure is obtained.

The slide-valves *D D'*, instead of being arranged in the chest *A³*, are located at the bottom of the cylinders intermediately between the piston-heads and made to conform at their under side to the curvature of the bottom of the cylinders *A A'*.

The slide-valves *D D'* are provided, like the suspension-carriage of the pistons, with longitudinal grooves (which grooves may also be arranged in the cylinders) and supported on anti-friction balls *e*, by which the friction of the slide-valves on the bottom of the cylinders is reduced and the motion rendered easy, so as to exert no drag on the pistons. The lateral shifting of the slide-valves *D D'* is prevented by fixed transverse guide-rods *f*, that are secured to the cylinders, as shown in Fig.

3, and extended across the top of the slide-valves, said rods working in connection with stops f' at the top of the slide-valves, so as to keep the slide-valves in proper position over 5 the ports while in transportation, as well as during the working of the meter.

The slide-valves D D' are arranged with central lugs, g , at the ends, which form alternately contact with the end disks of the pistons, which move thereby the slide-valves alternately in opposite directions, as shown in 10 Figs. 1 and 5.

The gas outlet ports are opened or closed by the slide-valves D D' when the pistons are 15 near the end of each stroke.

The piston and slide-valve of one cylinder control the outlet of gas for the piston of the other cylinder, as customary in piston meters of this class. The gas enters to the interior of 20 the cylinders A A' of the meter through the inlet-pipe h , that is located at the center of one of the cylinders, as shown in Figs. 2 and 3. The gas fills the space of both cylinders between the end disks of the pistons, as the longitudinal partition between the same is open at 25 the middle portion. The gas passes from the spaces between the end disks of the pistons to the open outlet-ports h' at the lower part of the cylinders, and from the same through diagonal channels at the bottom of the casing to 30 the spaces between the end disks of the pistons and the heads of the casing, so as to move the pistons in opposite directions and shift thereby the slide-valves in both cylinders. The gas is 35 conducted off from the spaces between the opposite disks of the cylinders and the heads of the casing by the diagonal channels to the parts below the slide-valves and discharge-ports and channel h^2 , as shown clearly in Figs. 40 1, 2, and 3.

The diagonal connecting channels are made in the form of the pipes F F, and are attached by short offsets to the bottom of the inclosing-casing of the meter, and rigidly secured thereto 45 by bails f^2 and fastening-bolts f^3 , in the same manner as shown in my former patent referred to.

The general arrangement of the cross-pipes and the operation of the meter is the same in the patent before mentioned, the essential feature of novelty in this application being the suspending and balancing of the pistons from anti-friction carriages, the arrangement of the slide-valves at the bottom of the cylinders between the end disks of the pistons, and the reduction of the friction of the slide-valves with the bottom of the cylinders by the anti-friction balls.

Having thus described my invention, I claim as new and desire to secure by Letters Patent— 60

1. The combination of an inclosing-casing formed of two cylinders, reciprocating pistons in said cylinders, carriages guided on ways of the chest, anti-friction rollers between said carriages and the ways, and suspension-rods 65 connecting the carriages and pistons, substantially as set forth.

2. The combination of an inclosing-casing having a chest at the upper part and a bottom with vertical passages, reciprocating pistons 70 formed of end disks, connecting-stems, anti-friction carriages guided on ways of the chest, suspension-rods connecting the carriages with the stems of the pistons, slide-valves located at the bottom of the cylinders between the end 75 disks of the pistons, and outlet-ports and diagonal cross-channels at the bottom of the casing, substantially as set forth.

3. The combination of an inclosing-casing formed of two cylinders, reciprocating pistons 80 in said cylinders, carriages guided on ways of the chest, suspension-rods connecting the carriages and pistons, slide-valves located at the bottom of the cylinders and operated by the pistons, inlet and outlet ports, and diagonal 85 channels at the bottom of the casing, substantially as set forth.

In testimony that I claim the foregoing as my invention I have signed my name in presence of two subscribing witnesses.

AUGUST C. CHRISTENSEN.
